UNITED STATES PATENT OFFICE.

HAROLD W. SHONNARD, OF UPPER MONTCLAIR, NEW JERSEY, ASSIGNOR TO ELEVATOR SUPPLIES COMPANY, A CORPORATION OF NEW JERSEY.

ELEVATOR DOOR.

Continuation of application Serial No. 31,783, filed May 21, 1925. This application filed December 23, 1926. Serial No. 156,557.

In my application for United States Letters Patent filed March 17, 1925, Serial Number 16,214 I have described means for avoiding accidental catching of fingers and clothing of passengers in doors for elevators, etc., constructed of metal strips pivotally connected and acting on the "lazy tongs" principle. The means in question comprise one or more flexible curtains on a spring roller or rollers 10 so arranged that, as the door is unfolded in closing, the curtain unrolls and presents a shield along the expanding width of the door; at the same time, of course, winding up the spring on the roller and increasing its tension.

In order to prevent sagging of the flexible curtain so used it is necessary to employ a roller spring of very considerable tension; and, in consequence, it has been found that 20 the pull of the curtain on a closed elevator door is sufficient to open the door to some extent, unless it be held or locked closed, which is not acceptable in practice. This accidental opening of the elevator door is particularly undesirable in the numerous cases 25 in which an electric "interlocking switch" is so operated by the closure of the door, even a little distance, in such cases, acts to bring the elevator cage to a stop at once.

30 The present invention has relation to means for preventing all disadvantages arising from the tension of the roller spring of my improved flexible shield above mentioned, these means involving a counterbalancing device 35 adapted to easy application to an elevator door, and fitted for accommodation within the restricted space available in standard elevator structures.

In some cases it is the practice to provide 40 automatic closing devices for elevator doors, and, where unbalanced spring-roller shields are used, these power closers have to be specially adjusted for use with each door, owing to differences in spring tension and in the 45 range of door movement. My present invention renders such adjustment generally unnecessary, as the disturbing influence of each spring-pulled shield or curtain is removed. The present application is a continuation 50 of my patent application for closing means for elevator doors, filed May 21, 1925, Serial No. 31,783 which has become abandoned.

My invention is illustrated in a preferred form in the accompanying drawing wherein 55 Figure 1 is a view in elevation of a mechanically operated door equipped with my invention, Figure 2 is a view on a larger scale of my spring counterbalance, as seen in elevation, Figure 3 is a plan view of the same, and 60 Figure 4 is a perspective view of a preferred form of attachment for the tension chain.

In the particular form shown in the drawings, the door is operated by a form of mechanical means set forth and claimed in another patent application. This comprises a compressed air engine 7 acting through a swinging arm 8 which has a sliding attachment 9 with the door or gate. This forms no part of the present invention, as any appropriate form of mechanical door operator 70 may be used in connection with the invention described below.

The well known "lazy tongs" door or gate is composed of parallel vertical bars 10 united 75 by diagonal bars 11, pivotally connected with each other and slidingly connected with the verticals. As the door is expanded to close it, the verticals move apart retaining their parallelism and the diagonals make an increasing angle with each other.

The flexible shield of my aforesaid pending application comprises a curtain 12, whose outer edge is fixed to the outer edge of the door or gate, as shown. This curtain is carried by a spring roller 13 fixed usually to the door jamb, as shown. It will be clear that the constant tension of the spring roller 13 acts through the curtain 12 to tend to open the door.

In order to counterbalance this tendency, I employ one or more helical springs 14, so arranged as to pull the door shut. Springs of this kind cannot be extended in practice for more than about thirty percent of their 95 unextended length. An extension materially greater than this carries them beyond the elastic limit, and soon renders them useless. It is clear, therefore, that if a spring or spring-group were attached to the outer 100 edge of the unfolding door or gate, the extension of the spring would have to be at least as great as the entire width of the door opening. Consequently it would be necessary to use a spring group about six feet long. 105 This would be awkward in any connection,

but it is quite impracticable in elevator practice, because the entire equipment for each elevator has to be placed within the lateral limits of its own shaft and cage.

5 My invention, in its preferred form, therefore, comprises a construction such as to permit a practical spring to be located within the width of the elevator cage, which is very generally only slightly greater than the door opening itself.

10 For this purpose I preferably employ a tension member having a spring or spring group 14, one end of which tension member is fixed, as shown, to an extension 10^a on one 15 of the vertical bars 10 contiguous to the jamb whereon the door is hung. In the drawing the second movable vertical is shown, but the choice of verticals for this purpose will depend upon the maximum distance between 20 verticals, the strength of the spring group etc.

25 The opposite end of the tension member preferably consists of a chain 15 which is fixed to a suitable fastening on that side of the door frame opposite to the jamb upon 30 which it is hung. In order to suit a given tension member to doors of different width and to spring rollers 13 of different tension, I prefer to make the attachment of the chain 15 an adjustable one.

35 For this purpose I provide a bracket 16, preferably of malleable iron, so that it can be easily bent. The projecting portion of this bracket has a deep slot 17, of proper width to receive the narrow end of a link 15 while 40 not permitting passage of the wider end of such link. The initial tension of the spring group 14 can be adjusted within limits by catching one or another of the links of the chain 15 in the slot 17.

45 If desired, the opening of the slot 17 can be more or less closed after insertion of the chain, so as to hold it in place, by a few taps of a hammer on the bracket 16. This last named feature makes it possible to use the 50 same tension member on right or left-handed doors at will. When attached as shown in the drawing the chain 15 lies in a slot 17 open at the top, and the slot need not be closed, as the chain cannot fall out. The same tension member could, however, be used with a door opening oppositely to that shown, in which case the slot 17 would be inverted and would

have to be closed as above described to prevent the chain from falling out.

55 It will now be seen that, inasmuch as the ratio of the total horizontal movement of a given vertical bar 10 to the width of the door opening is expressed by a fraction whose denominator is the number of spaces between verticals and whose numerator is the number 60 of such spaces between the given vertical and the door jamb; it is clear that the total travel of one of the verticals contiguous to the jamb is in that ratio smaller than the width of the door opening. Consequently, when the tension member is mounted as shown, its total extension during use is much less than if it were attached to the front edge of the door. This makes it possible, therefore, to accommodate the entire door closing counterbalance 70 within the width of the elevator cage.

What I claim is—

1. In combination with an elevator car, a gate, mechanical means for operating the same, a spring operated fender on the gate and 75 a spring having one end attached to the frame of the gate and the other end attached to the gate, said spring being adapted to counterbalance the tension of the fender spring so as to prevent disturbance of the action of the gate operating means.

2. According to claim 1, the counterbalance spring comprising an extensible helical spring or springs, a chain attached to one end thereof, and a slotted bracket adapted to engage 85 with one or another link of said chain to permit adjustment of the spring tension at will.

3. According to claim 1 the counterbalance spring comprising an extensible helical spring or springs, a chain attached to one end thereof, 90 and a reversible bracket having a slot adapted to be partly closed and adapted to engage with one or another link of said chain to permit adjustment of the spring tension at will.

4. In an elevator car a "lazy tongs" gate 95 for the same having vertical bars and cross bars pivoted to said vertical bars, a spring operated fender on said gate, and a spring having one end attached to the frame of the gate and the other end attached to an extension on a vertical bar thereof near the movable outer edge of the gate.

In testimony whereof I affix my signature.

HAROLD W. SHONNARD.
